DESIGN FOR A TRACTOR

Herbert C. Roths, Alpena, Mich.

Application August 24, 1945, Serial No. 124,956

Term of patent 14 years

(Cl. D14—3)

To all whom it may concern:

Be it known that I, Herbert C. Roths, a citizen of the United States and a resident of Alpena, in the county of Alpena and State of Michigan, have invented a new, original, and ornamental Design for Tractors, of which the following is a specification, reference being had to the accompanying drawing, forming a part thereof.

In the drawing:

Fig. 1 is a side, perspective view of a tractor, showing my design;

Fig. 2 is a top plan view thereof;

Fig. 3 is a front perspective view of the tractor; and

Fig. 4 is a front perspective view thereof.

The characteristic features of my design reside in the portions shown by means of full lines in the drawing.

I claim:

The ornamental design for a tractor, as shown and described.

HERBERT C. ROTHS.
